(57) **CLAIM**

The ornamental design for a toy robotic arm, as shown and described.

DESCRIPTION

FIG. 1 is a perspective view of a toy robotic arm showing my new design;

FIG. 2 is another perspective view thereof;

FIG. 3 is still another perspective view thereof;

FIG. 4 is the other perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken line showing of the toy robotic arm is for the purpose of illustrating portions of the article and forms no part of the claimed design.
